ROTOGRAVURE PRINTING PROCESS

Arthur W. Raby, Toronto, Ontario, and George R. Harvey, Cooksville, Ontario, Canada, assignors to The Toronto Star, Toronto, Ontario, Canada

Application June 9, 1938, Serial No. 212,672

8 Claims. (Cl. 95—5.7)

This invention relates to the process of preparing a printing surface on copper surfaced rolls for the reproduction of photographic subjects and the principal objects are to overcome 5 some of the major difficulties met with in the preparation of the etched surfaces for intaglio printing, and to produce prints in which the shadow portions will be of uniform tone.

The principal features of the invention consist 10 in the novel steps in the process of creating an intaglio printing surface in which deep shadows are produced having an intaglio reproduction of a combination of half-tone dots and a fine mesh screen, the intersecting lines of the screen forming 15 a grid surface enclosing a multiplicity of intaglio recesses interspersed between the ordinary half-tone dot recesses.

In the accompanying drawing Figure 1 is an 20 enlarged representation of a portion of a picture illustrating the arrangement of ordinary half-tone dots on a screened negative.

Figure 2 is a similar illustration of the arrangement of fine intersecting screen lines on 25 a film positive.

Figure 3 is a representation of a contact film 30 positive produced by a combination of the half-tone dot screen negative and the line screen positive which is produced in intaglio on the copper plate by etching.

Figure 4 is an enlarged detail showing the arrangement of half-tone dots and screen in intaglio.

In carrying this process into effect a continuous tone negative is first produced by photographing the object. This negative is suitably 35 retouched and from this negative is produced a continuous tone positive which in turn is suitably retouched. To this point the process is the same as is practiced in the ordinary gravure process.

A screened half-tone negative is then made from the retouched positive as illustrated in Figure 1 of the drawing.

A very contrasty negative film print is then 45 made from the retouched positive and from this is printed a film positive, with a fine line mesh screen interposed, producing a screen shape, the main characteristic of which, is that the deep shadows are reproduced in the form of intersecting fine lines as illustrated in Figure 2. This fine line mesh screen may be termed a "gravure" screen and is characterized by its extreme fineness compared to the usual half-tone screen.

The next step is to carefully combine the 50 halftone negative of Figure 1 with the screen

shape positive of Figure 2 to produce a final positive representation as illustrated in Figure 3 in which all tones are represented by half-tone dots of varying sizes except in the deep shadow portions and in such portions there is 5 a combination of half-tone dots and screen.

It will be noted as illustrated in Figure 2 that the screen positive is a flat or uniform tone and has no influence on the gradation of the image which is carried by the half-tone dots, but the 10 screen being superimposed on the deep shadow surfaces, forms a bearer surface formed of a combination of dot and line screen.

When the final positive, which is represented by Figure 3, is completed it is placed directly 15 over the copper plate or cylinder which has been previously prepared with a sensitized coating, and it is then "exposed" to light in the usual manner of producing a resist print, after which it is developed and fixed ready for etching. 20

The etching is accomplished in a single operation and produces over the ordinary light-tone surfaces an arrangement of intaglio recesses of varying sizes to produce the final printing effect of the shaping and gradation of the image and 25 in those places where the fine line screen is interposed the surface is etched to form a multiplicity of intaglio recesses separated by the fine lines of the screen in the metal between the dot recesses. 30

It will be readily understood by those skilled in the art, that where deep shadows occur and particularly where such shadows cover comparatively large areas, the body of ink on such areas will be very effectively retained against being 35 gouged or wiped out, with the result that the ultimate picture produced in the printing will be featured by solid uniform colour tone, which is the principal objective. Further it will be readily appreciated that the various steps in achieving the desired result are of a simple nature 40 ensuring accurate results.

It will also be appreciated that the present process introduces into gravure printing the use of the half-tone screen which, by reason of the 45 outer exposure of paper surface, produces a much more luminous type of print and a better working medium which enables a more faithful reproduction.

What we claim as our invention is:

1. A rotogravure printing process comprising incorporating into a final positive film of the image to be reproduced a combination of half-tone dots and screen lines by contact exposure thereof through a superimposed half-tone screen 50

negative and a contrasty continuous tone negative and a transparent line screen so that said positive presents closely spaced screen lines in the shade areas only of the image, exposing a sensitized metal surface through the resultant positive of the image to be reproduced, developing and finally etching the metal surface.

2. A rotogravure printing process comprising, forming a half-tone negative by exposure 10 through a half-tone screen, forming a screen-line positive by exposure of predetermined areas only thereof through a gravure screen, and combining the half-tone negative image with the screen line positive and reproducing the combined effect thereof on a sensitized metal printing surface by the exposure, developing and etching process.

3. A rotogravure printing process comprising first producing a continuous tone positive and a 20 half-tone screen negative, then from said continuous tone positive producing a contrasty continuous tone negative, then placing said continuous tone negative together with a screen having fine and closely spaced transparent intersecting 25 lines over a sensitized film and exposing the latter therethrough to produce a transparent medium having light-obstructing screen lines confined to areas representing the shadow portions of the image, then by the contact and exposure method effecting the transfer of the half-tone screen and line images respectively of said half-tone screen negative and said transparent medium to a transfer medium, and utilizing said transfer medium for the reproduction of the 30 combined half-tone and screen line effect on a metal printing surface.

4. A rotogravure printing process comprising first producing a continuous tone negative, then from the negative producing a positive continuous tone image, then from the positive producing a half-tone screen negative, from the continuous tone positive producing by superimposition a negative mask having light-penetrable areas corresponding to the dark or shaded areas of said 40 positive, from the mask producing a screen-line positive by exposure of a light-sensitive layer through a fine line screen, combining by superimposition the screen line positive and half-tone screen negative to produce a positive, placing a light sensitive coating on a metal surface, exposing said coating through the said combined half-tone and line screen positive, and etching the metal surface to produce an intaglio printing plate.

5. A rotogravure printing process comprising

first producing a half-tone screen negative and a continuous tone positive, then from said continuous tone positive producing a contrasty continuous tone negative, then placing said continuous tone negative together with a screen having fine and closely spaced transparent intersecting lines over a sensitized film and exposing the latter therethrough to produce a transparent medium having light-obstructing screen lines confined to areas representing the shadow portions of the image, then by the contact and exposure method producing from said half-tone screen negative and said transparent medium a transparent film positive, and then by the contact, exposure and etching method reproducing 15 said positive on a metal printing surface.

6. A rotogravure printing process comprising, forming a half-tone negative by exposure through a half-tone screen, forming a screen-line positive by exposure of predetermined areas 20 only thereof through a gravure screen, the gravure screen lines of which are spaced more closely than the rows of half-tone dots, and combining the half-tone negative image with the screen line positive and reproducing the combined effect thereof on a sensitized metal printing surface by the exposure, developing and etching process.

7. A rotogravure printing process comprising, forming a half-tone negative by exposure 30 through a half-tone screen, forming a screen-line positive by exposure of predetermined areas only thereof through a gravure screen, and combining the half-tone negative image with the screen line positive with the gravure screen lines 35 acutely intersecting the rows of half-tone dots and reproducing the combined effect thereof on a sensitized metal printing surface by the exposure, developing and etching process.

8. A rotogravure printing process comprising, forming a half-tone negative by exposure through a half-tone screen, forming a screen-line positive by exposure of predetermined areas 40 only thereof through a gravure screen, the gravure screen lines of which are spaced more closely than the rows of half-tone dots, and combining the half-tone negative image with the screen line positive with the gravure screen lines 45 acutely intersecting the rows of half-tone dots and reproducing the combined effect thereof on a sensitized metal printing surface by the exposure, developing and etching process.
